UNITED STATES PATENT OFFICE

2,649,552

PRESSURE-STARTING MOTOR
CONTROL DEVICEKenneth D. Burrell and Richard C. Latson,
Zephyrhills, Fla.

Application July 11, 1950, Serial No. 173,026

1 Claim. (Cl. 310—68)

1

This invention relates to motor-driven hand tools, and more particularly to an electrically-driven hand tool suitable for buffing, polishing, sanding, and the like.

A main object of the invention is to provide a novel and improved motor-driven hand tool which operates responsive to pressure exerted on the tool element thereof, the hand tool being de-energized when no pressure is exerted on its tool element, the device being very simple in construction, being easy to operate, and providing a saving in electric power.

A further object of the invention is to provide an improved electrically-driven hand tool of the type employed in sanding, polishing, buffing, and similar operations, said tool being inexpensive to manufacture, being sturdy in construction, involving relatively few parts, and being easy to take apart for servicing or for replacement of the tool element thereof.

Further objects and advantages of the invention will become apparent from the following description and claim, and from the accompanying drawings, wherein:

Figure 1 is a longitudinal, cross-sectional view taken through an improved electrically-driven hand tool constructed in accordance with the present invention;

Figure 2 is an enlarged, cross-sectional, detail view taken on line 2—2 of Figure 1.

Referring to the drawings, 11 designates a housing adapted to be held by the user, and 12 designates an electric motor fixedly secured inside the housing by any suitable means, not shown. The shaft of the motor is designated at 13, one end of said shaft being rotatably journaled in a suitable bearing 14 provided in the end wall of housing 11, the opposite end portion of the shaft being rotatably supported in a bearing 15 mounted in a transverse partition wall 16 provided in the housing 11. Rigidly secured on the shaft 13 outwardly adjacent the bearing 15 is a collar or flange 17. The shaft 13 extends outwardly from the housing 11 and is formed at its outwardly extending portion with a longitudinal keyway 18. Designated at 19 is a sleeve member which fits slidably over the outer end portion of the shaft 13 and is formed with an integral, longitudinal key 20 which is slidably received in the keyway 18. The sleeve member 19 extends rotatably through a bushing 21 which is threaded into the end wall of the housing 11, as shown at 22, the sleeve member 19 being formed with an end annular flange 23. Designated at 24 is a coil spring which encircles the shaft 13 and bears at one end on the collar 17, and at the other end on 55

2

the flange 23, biasing the sleeve member 19 outwardly to a position wherein the flange 23 abuts the inner rim of the bushing 21. Designated at 25 is a disc member carried on the end of the sleeve member 19, said disc member being, for example, a sanding disc, a buffing disc, a polishing wheel, or any other desired tool.

Secured in the compartment of the housing designated at 26, as viewed in Figure 1, is a supporting member 27 of insulation material, said supporting member extending at right angles to the shaft 13, and secured on said supporting member are the respective contact members 28 and 29. The contact member 29 comprises a resilient arm which is provided at its end with a contact element 30, the contact member 28 being provided with a similar contact element 31. When the flange 23 is in abutment with the inner edge of the bushing 21, as shown in Figure 1, the contact elements 30 and 31 are in separated positions. The flange 23 has secured to its outer surface an annular rim 32 of insulation material which is adapted to engage the contact arm 29 responsive to movement of the sleeve member inwardly with respect to housing 11, engagement of the rim 32 with the contact arm 29 being sufficient to flex the contact arm 29 counterclockwise, as viewed in Figure 1, forcing the contact member 30 into engagement with the contact member 31. This action occurs when the tool element 25 is pressed against the surface to be engaged by the tool element, as for example, the surface of a floor to be sanded, or a surface to be polished. The contacts 30 and 31 are connected in series with the energizing circuit of the motor 12, whereby the motor 12 becomes energized as soon as the aforesaid contact elements 30 and 31 are engaged with each other. Therefore, in operating the device, the motor 12 is normally de-energized, but as soon as the tool element 25 is pressed against the surface to be polished, sanded, or the like, the motor becomes energized and the operation of the tool commences. As soon as pressure is released on the tool element 25, the spring 24 forces the flange 23 into abutment with the inner edge of the bushing 21, namely, to the position shown in Figure 1, thereby releasing the flexible contact arm 29 and opening the motor-energizing circuit.

The surface of the insulating bead 32 is preferably smoothly rounded and highly polished, and said bead element is made of material having a high resistance to abrasion, whereby the bead 32 may rotate relative to the contact element 29 without undue wear thereof.

When it is desired to change the type of tool

element driven by the device, the bushing 21 is unscrewed, allowing the sleeve member 19 and said bushing to be removed and to be replaced by the bushing associated with the sleeve element of the new tool element to be employed with the device.

While a specific embodiment of an improved electrical tool of the motor-driven type has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

An electrical tool of the character described comprising a housing, an electric motor mounted inside said housing, a tool member, a sleeve element carried by said tool member and being slidably and non-rotatably engaged on the motor shaft and extending outside the housing, spring means biasing said tool member outwardly relative to the housing, a stationary switch contact mounted in said housing and extending substantially parallel to said shaft, a flexible switch contact mounted in said housing inwardly adjacent to said stationary contact and being bendable into engagement with said stationary switch contact, said flexible switch contact being normally parallel to and disengaged from said stationary

switch contact, an annular flange on said sleeve element having a radius greater than the distance of said flexible contact from the axis of the shaft and having a rounded outer rim which is normally spaced axially outwardly from said flexible contact and is engageable with said flexible switch contact to move the flexible contact radially outwardly into engagement with the stationary contact responsive to inward axial movement of the tool member relative to the housing, and a normally open energizing circuit connected to said motor and including said contacts in series therewith and being arranged to be closed responsive to the closure of said contacts.

KENNETH D. BURRELL.
